UNITED STATES PATENT OFFICE.

HARRY D. FORSE, OF ANDERSON, INDIANA.

ALL-METAL KNOCKDOWN TOY VEHICLE.

Application filed August 14, 1924. Serial No. 732,029.

To all whom it may concern:

Be it known that I, HARRY D. FORSE, a citizen of the United States, and a resident of Anderson, county of Madison, and State of Indiana, have invented a certain new and useful All-Metal Knockdown Toy Vehicle; and I do hereby declare that the following is a full, clear, and exact description thereof, reference being had to the accompanying drawings, in which like numerals refer to like parts.

This invention relates to a toy vehicle of the tricycle type propelled by the feet either through pedals or by direct engagement of the foot with the vehicle supporting surface.

The chief object of the invention is to construct a toy vehicle of the character indicated substantially entirely of metal whereby the same is relatively indestructible and can be very economically produced.

Another object of the invention is to construct an all metal vehicle of the character indicated in such a manner that the same can be knocked down for shipping purposes so that when knocked down or collapsed it occupies very little space.

The chief feature of the invention consists of the construction of the same whereby the two foregoing objects are accomplished and incidental features of the invention relate to the details of construction, said features being pointed out hereinafter more in detail.

The full nature of the invention will be understood from the accompanying drawings and the following description and claims:

Fig. 1 is a top plan view of the invention.

Fig. 2 is a central sectional view of the same and is taken on line 2—2 of Fig. 1 and in the direction of the arrows.

Fig. 3 is a front view of a portion of the steering wheel, parts being shown in section to show other parts in detail.

Fig. 4 is a view similar to Fig. 3, but of a modified form of construction.

Fig. 5 is a sectional view taken on line 5—5 of Fig. 1 and in the direction of the arrows.

Fig. 6 is a sectional view of a modified form of steering wheel.

In the drawings the seat portion includes the largest or back portion 10, a neck 11 and a head 12. Extending peripherally around the aforesaid seat portion is a flange 13 which is tapered downwardly and outwardly. The head portion 10 is suitably

apertured as at 14 and associated therewith is a bearing construction. Said bearing construction includes a pair of metallic collars 15 and 16 suitably secured together and to the seat portion. Each of the collars and the head portion 12 are provided with registering openings, thereby providing a pivot support having three superposed or parallel bearing rings.

The neck portion of the seat is suitably depressed as at 17 and is apertured as at 18, said depression being concentric with said aperture. A centering headed bolt 19 extends through the aperture 18 and carries a lock washer 20 and a wing nut 21. The aforesaid construction is centrally positioned with respect to the vehicle.

Adjacent the rear portion of the back 10 and formed in said peripheral flange 13 is a depressed portion 121, which is apertured as illustrated and suitably supported in said aperture is a rivet or pivot 22. The upper free end of a U-shaped construction having the arms 23 and connecting portion 24 is thus pivotally supported at the pivotal support 22. The pivotal support 22 is transversely positioned with respect to the pivotal support defined by collars 15 and 16, and the central aperture 14.

Near the opposite end of said arms forming the U-shaped member are the openings 25 and positioned in said openings 25 is a shaft 26. A U-shaped strap having the two relatively adjacent portions 27 connected by the curved portion 28 is shown provided near said connection with an enlargement or offset portion 29. The arms 30 extend in twisted relation both outwardly and downwardly as shown. The free ends are bent angularly thereof as at 31 and they are apertured as at 32, which aperture registers with the aperture 25 to receive the shaft 26.

As shown clearly in Figs. 1 and 2, the depression or offset portion 29 is adapted to engage the depressed portion 17 and to prevent forward longitudinal movement parallel to the seat. Likewise, the bolt 19 by being positioned as shown cooperates with connecting portion 28 and the side portions 27 and prevent both lateral movement and longitudinal movement rearwardly of the seat. The brace construction, therefore, is adapted to be rigidly secured, although detachably mounted for knocking down purposes.

Upon the extending end of the shaft 26

there is pivotally mounted a wheel of any suitable character and herein the same includes a bushing 33, the disk portion 34 and the tread portion 35. A metal cap 36, as shown in Figs. 1 and 5, is adapted to cover the bare end of the shaft 26 and a cotter key 37 is adapted to connect the two together and thus anchor all of the aforesaid construction together.

10 The U-shaped brace formed from a single strip of strap metal and the U-shaped bolster formed from similar material are thus secured together, but permit of a collapsible arrangement as follows; by removing cotter key 37 and cap 36, the rear wheels can be readily detached from the axle and the axle may be removed from the two U-shaped co-operating members, to-wit, the brace and the bolster. Removal of the axle as aforesaid permits separation of the brace and bolster. If said axle is not removed then to collapse the brace and bolster construction, the nut 21 is loosened to permit the escape of the U-shaped brace from bolt engagement and when thus freed, the brace may be extended forwardly and thence turned upon the axle 26 as a pivot and thence rearwardly. At the same time, the U-shaped bolster may be moved forwardly upon the pivot 22 so as to lie substantially parallel to the seat portion.

15 The dimensions of the back may be such that the wheels will just clear the same and lie in the space immediately adjacent the junction of the neck portion with the back portion. All of these various combinations of arrangements or knock down positions may be utilized as found desirable or necessary without departing from the broader features of the invention. The U-shaped bolster, it is to be understood, limits the inward movement of the wheels along the axle, while the outward movement thereof is limited by the ornamental protective retaining cap.

20 The steering wheel includes the tread portion 40, the supporting disk portions 41, and the bushing or sleeve 42. As shown clearly in Fig. 3, said bushing or sleeve portion is polygonal in cross section. A multiple crank construction is associated therewith and herein said cranks are identical. The offset portion 43 supports a washer 44 retained thereon by the enlargements 45. A pedal construction 46 is retained on said offset portion 43 by another washer 47, the same being held together by the enlarged head portion 48. The opposite end of the crank 49 is rotatably supported in a strap 50 suitably apertured as at 51. The extending end

25 52 is suitably provided with a polygonal outline and preferably of such area that it exceeds the area of the opening 51 and thus secures said strap 50 to the crank construction. A pair of said cranks is associated with a pair of said straps and said cranks,

that is, the polygonal ends 52 thereof, are receivable by the polygonal bushing 42. The straps 50 extend upwardly and inwardly and thus form one branch of the fork or yoke construction which supports the steering wheel. The two straps are suitably formed immediately above the tread portion 40 so that they extend towards each other as at 53, thereby completing a full fork. Said inwardly extending ends are suitably curved 75 into semi-cylindrical form as at 54 and together form a cylindrical post, which as shown clearly in the several figures is receivable by the first mentioned pivotal support including the collars 15 and 16 and the registering opening 14 in the head 12. The free ends of said curved portions 54 project beyond said pivotal support and are suitably apertured as at 55. A rod 56 is likewise apertured and said apertures 55 register with each other and the rod aperture.

30 A single securing member 57 is adapted to detachably but rigidly secure the two portions of the steering fork together and to the rod and also secure the aforesaid construction to the seat. The upper end of the rod 56 is adapted to suitably support any desired or preferred handle herein conventionally illustrated and indicated at 157.

35 It will be readily observed that each of the portions of the fork and the associated crank is detachable for knocking down purposes. The lower collar 16 retains said fork members in fork-forming position which prevents the longitudinal and outward movement of the crank portions from the wheel forming bushing 42. The individual escapement of said crank portions from the yoke forming portion is prevented as previously pointed out by the enlargement 52. 105 When a tricycle of the character indicated provided with pedals is not desired, the two fork forming portions 50 are secured together rigidly by means of a pivot pin upon which the bushing 42 would rotate, said 110 bushing in this instance being preferably cylindrical in character see Fig. 6.

40 In Fig. 4 there is illustrated a modified form of construction and in this form of construction the bushing 142 and the disks 141 are suitably notched and the fork members 150 are associated therewith by means of the cranks 149. The cranks 149 include the offset portions which carry a locking pin 152 which is the equivalent of the enlargement 52, that is, it prevents separation between the fork and the crank and insures rotation of the wheel when the crank is actuated.

45 The invention claimed is:

50 1. A knockdown toy vehicle comprising a seat having at opposite ends a pair of pivotal supports substantially transverse to each other, one being substantially transverse to the plane of the seat and the other 130

being substantially parallel thereto, a steering wheel construction detachably mounted in the transverse pivotal support, a bolster pivotally connected to the parallel pivotal support, a U-shaped brace forming strap having its mid-portion curved for detachable connection to the seat and its free ends extending outwardly, downwardly and rearwardly and secured to the lower portion of the bolster, and means positionable in the mid-portion of the curved strap for securing the same to the seat.

2. A knockdown toy vehicle comprising a seat having at opposite ends a pair of pivotal supports substantially transverse to each other, one being substantially transverse to the plane of the seat and the other being substantially parallel thereto, a steering wheel construction detachably mounted in the transverse pivotal support, a U-shaped bolster forming strap pivotally connected to the parallel pivotal support, a U-shaped brace forming strap having its mid-portion curved for detachable connection to the seat and its free ends extending downwardly, outwardly and rearwardly and secured to the U-shaped bolster strap near the lower end thereof for securing the same in bolster position, and means positionable in the curved portion of the strap for securing the same to the seat.

3. In a knock down toy vehicle of the character described, the combination of a seat portion having a projection upon its under surface, a U-shaped twisted brace, and a bolt construction detachably connecting said brace at its mid-portion to said seat adjacent the projection, said brace having a cooperating portion engageable by said projection for limiting longitudinal movement of said brace in the direction of the intermediate portion thereof and the bolt construction engaging the intermediate portion of said brace for limiting the movement of said brace laterally and in a direction toward the projection.

4. In a knock down toy vehicle of the character described, the combination of a seat including a pivotal support, a steering wheel construction comprising a wheel supported by strap means extending upwardly towards said seat in fork formation and terminating in semi-cylindrical bearing portions pivotally connected to said seat pivotal support, a handle telescopically connected to the projecting end of said fork forming strap means, and means for locking said strap ends together and to the telescopically connected handle for securing the same to-

gether and for securing the wheel construction to the seat.

5. In a knock down toy vehicle of the character described, the combination of a pair of straps having their upper ends detachably connected together and arranged to form a pivot and a yoke, a wheel adapted to be straddled by said yoke, and a pair of pedal cranks each mounted upon the lower end of a strap and detachably connected to said wheel.

6. In a knock down toy vehicle of the character described, the combination of a pair of straps having their upper ends detachably connected together and arranged to form a pivot and a yoke, a wheel adapted to be straddled by said yoke, a pair of pedal cranks each mounted upon the lower end of a strap and detachably connected to said wheel, and a complementary connection between the wheel supported ends of said cranks and said wheel for rotating the wheel with the crank and adapted to secure said crank to its adjacent fork forming support.

7. In a knockdown juvenile vehicle, the combination of a pair of fork forming straps, each having one end complementarily formed to make a pivot, a wheel, a pair of cranks, each pivotally mounted in the other end of one of said straps and permanently secured thereto and receivable by said wheel for driving engagement and wheel supporting purposes, and means securing the pivot making strap portions together for forming a wheel fork.

8. In a toy vehicle of the character described, the combination of a seat including an aperture for a pivotal support, a handle extending towards the seat, wheel means positioned beneath the seat, a pair of fork forming straps supporting said wheel means at their lower ends and having an intermediate portion turned inwardly towards each other in fork formation and upper ends substantially semi-cylindrical in form for forming a bearing, said semi-cylindrical portions of said straps and said handle having a telescopic connection adjacent the seat and at least one of said telescopic connecting portions extending through said seat aperture and pivotally supported therein, and means simultaneously securing the telescopic ends of said fork and said handle together in steering wheel formation.

In witness whereof, I have hereunto affixed my signature.

HARRY D. FORSE.
